UNITED STATES PATENT OFFICE.

BENJAMIN BERNARD BLEY, OF WACO, TEXAS.

DESIGN FOR A SET OF PLAYING CARDS.

Application filed June 7, 1922. Serial No. 2,560. Term of patent 14 years.

To all whom it may concern:

Be it known that I, BENJAMIN B. BLEY, a citizen of the United States, residing at Waco, in the county of McLennan and State of Texas, have invented a new, original, and ornamental Design for a Set of Playing Cards, of which the following is a specification, reference being had to the accompanying drawings, forming part thereof.

The several figures from 1 to 66 are plan views of different cards of the set showing my new design.

I claim:

The ornamental design for a set of playing cards, as shown.

BENJAMIN BERNARD BLEY.
